UNITED STATES PATENT OFFICE

WILHELM B. BRONANDER, OF MONTCLAIR, NEW JERSEY, PETER M. NEJEDLY, OF BROOKLYN, AND LOUIS F. THIEL, OF SPRINGFIELD GARDENS, NEW YORK, ASSIGNEES TO AMERICAN MACHINE & FOUNDRY COMPANY, A CORPORATION OF NEW JERSEY

CUT-OFF FOR HIGH-SPEED CIGARETTE MACHINES

Application filed September 18, 1929. Serial No. 393,462.

This invention relates to cutoffs for continuous rod cigarette machines, particularly to cutoffs of the type in which the cutoff blade is moved in an orbital path oblique to the cigarette rod to cause the edge of the blade to traverse the rod and to follow its movement, without the necessity for longitudinal reciprocation of the blade and its driving parts.

The principal object of the invention is to produce a cutoff of this type in which all the moving supporting and driving parts for the cutoff blade have smooth rotary motion such that the cutoff is substantially vibrationless at very high speeds, as 2000 or more cuts per minute. Another object is to provide such a cutoff in which all heavy rotating parts are inherently balanced, thus eliminating vibration and the necessity for extensive counter-balancing. Another important object is to insure a square cut by providing driving means for the blade which maintains the blade perpendicular to the cigarette rod during the oblique orbital movement of the blade.

With these and other objects not specifically mentioned in view, the invention consists in certain constructions and combinations which will be hereinafter fully described and then more particularly pointed out in the claims hereunto appended.

In the accompanying drawings which form a part of this specification and in which like characters of reference indicate the same or like parts:

Fig. 1 is a sectional plan view of a cutoff constructed in accordance with the invention;

Fig. 2 is a side elevation of the cutoff, partly in section, with certain parts broken away;

Fig. 3 is an end view along the line 3—3 of Fig. 1, also partly broken away;

Fig. 4 is a plan view of a detail of the machine shown in Fig. 1, showing the relative positions of the parts as they approach cutting position; and

Fig. 5 is a view similar to Fig. 4, showing the positions of the parts as they leave cutting position.

In carrying the invention into effect, there is provided in combination with the usual

cutoff blade, mechanism for moving the blade in an orbital path oblique to the cigarette rod so as to cause the edge of the blade to traverse the rod and at the same time follow its movement; and this mechanism includes a shaft on which the blade is mounted, and spaced flying mounts for said shaft revolving respectively on axes laterally offset from each other for the purpose of maintaining the blade perpendicular to the rod during the oblique orbital movement of the blade. In the best constructions, said offset axes are parallel to each other. In the preferred form, the spaced flying mounts are carried on spaced parallel disks rotating respectively on the offset axes. The various means referred to may be widely varied in construction within the scope of the claims, for the particular device selected to illustrate the invention is but one of many possible concrete embodiments of the same. The invention, therefore, is not to be restricted to the precise details of the structure shown and described.

Referring to the drawings: The table 10 of the cigarette machine carries a stand 11 which supports bearing pedestals 12 and 13. A housing 14 is secured to bearing 12, a flange 15 of the bearing 13 fitting loosely into a ring 16 attached to the disk 20. A horizontal shaft 17 rotates in bearing 12 and supports at its inner end a circular disk 18 which, together with the similar parallel circular disk 20 similarly mounted on the shaft 19 in the bearing 13, drives the cutoff blade as herein-after described. The axes of the shafts 17 and 19 are oblique to the cigarette rod and are parallel and laterally offset from each other, as shown in Figs. 1, 4 and 5. The two disks 18 and 20 are connected by studs 21, each of which has two offset bearing portions in bearing plates 22 and 23 secured in the disks 18 and 20 respectively. These studs serve to impart the driving movement given to disk 18, by means herein-after described, to the other disk 20, and at the same time maintain the disks in predetermined relationship. The disks 18 and 20 carry respectively spaced flying mounts 26 for the shaft 24, on which shaft the knife 25 is rigidly mounted. These mounts have spherical bearing 100

portions for receiving the spherical journals 24a and 24b on the shaft 24. The cooperating spherical bearings and journals provide a flexible universal connection between the knife shaft and the disks at each mount.

A pin 28 is attached to the shaft 24 and fits loosely into the block 28a, slideable in an axial slot of disk 18, thus preventing the shaft 24 from rotating about its own axis. It is obvious that a circular knife could be employed without such means for preventing rotation of the shaft.

As shown in Figs. 1 to 5, the knife shaft and knife, by the above arrangement, will be carried as a whole in an oblique generally circular orbital path traversing the cigarette rod. As shown in Figs. 4 and 5, the amount and direction in which the parallel axes of the oblique disks 18 and 20 are laterally offset is just sufficient to render the axis of the knife shaft parallel to the cigarette rod. Since the disks are parallel and rotate together on parallel axes, the knife shaft will be held parallel and the blade perpendicular to the cigarette rod at all times and a perfectly square cut will be made.

For lubrication purposes, the cover 30 of the bearing 13 is provided with an oil reservoir 31 and disks 18 and 20 have annular oil grooves 32 connected by oil holes 33 with the bearing surfaces of the studs 21 and the shaft 24.

For the purpose of driving the disks 18 and 20, the shaft 17 is provided with a gear 35 meshing with a gear 36 on vertical shaft 37 supported in a housing 38 fixed at 39 to the bearing pedestal 12. The shaft 37 is also supported at its lower end by a bearing 40. The housing 38 terminates in a sleeve 41 which projects into a lower housing 42. The upper end of the bearing 40 projects into this housing 42 and carries suitable bearings for the support of the shaft 37. This shaft 37 has an eccentric portion 43 on which, by bearing 44, is mounted a ring 45 connected with a slide 46 on a shaft 49 for reciprocating the ledger plate in synchronism with the rotation of the knife carrying disks 18 and 20. A sleeve 47 surrounding shaft 37 terminates in a recessed flange 48 which catches the oil dripping from the housing 38 and leads it to the bearing 44.

The tubular ledger plate 54 is mounted in suitable lugs 52 integral with the slide 46. Motion is imparted to the shaft 37 from the main shaft of the cigarette machine by a gear 55 meshing with a gear 56 mounted on a horizontal shaft 57 connected to said main shaft of the machine.

A suitable grinding disk 58 is provided in the path of the edge of the knife 25. This disk rotates on a shaft 59 adjustable on its support 61 by a thumb screw 63 and is driven by the belt 69.

It will be seen from the foregoing that a

cutoff has been provided in which the cutoff blade is perpendicular to the rod and in which its edge follows the movement of the rod during cutting, all without any reciprocating parts in the cutoff drive; and that in this cutoff the main driving parts are two smoothly rotating disks which are inherently balanced and vibrationless. In view of the foregoing further description of the operation of the improved cutoff is deemed unnecessary and is omitted in the interest of brevity.

What is claimed is:

1. In a continuous rod cigarette machine, the combination with a cutoff blade, of mechanism for moving said blade in an orbital path oblique to the cigarette rod to cause the edge of the blade to traverse the rod and follow its movement, including a shaft for said blade, and oppositely disposed mounts in which said shaft is journaled revolving respectively on axes laterally offset from each other.
2. In a continuous rod cigarette machine, the combination with a cutoff blade, of mechanism for moving said blade in an orbital path oblique to the cigarette rod to cause the edge of the blade to traverse the rod and follow its movement, including a shaft for said blade, and oppositely disposed mounts in which said shaft is journaled revolving respectively on axes laterally offset from each other, said offset axes being parallel to each other.
3. In a continuous rod cigarette machine, the combination with a cutoff blade, of mechanism for moving said blade in an orbital path oblique to the cigarette rod to cause the edge of the blade to traverse the rod and follow its movement, including a shaft for said blade, oppositely disposed mounts in which said shaft is journaled revolving respectively on axes laterally offset from each other, and spaced parallel disks carrying said mounts and rotating on said axes.
4. In a continuous rod cigarette machine, the combination with a cutoff blade, of mechanism for moving said blade in an orbital path oblique to the cigarette rod to cause the edge of the blade to traverse the rod and follow its movement, including a shaft for said blade, oppositely disposed mounts in which said shaft is journaled revolving respectively on axes laterally offset from each other, spaced parallel disks supporting said mounts and rotating respectively on said axes, drive means for one of said disks, and driving connections between the last mentioned disk and the other of said disks.
5. In a continuous rod cigarette machine, the combination with a cutoff blade, of mechanism for moving said blade in an orbital path oblique to the cigarette rod to cause the edge of the blade to traverse the rod and follow its movement, including a shaft for said blade, and oppositely disposed mounts in

which said shaft is journaled revolving respectively on axes laterally offset from each other, spaced parallel disks supporting said mounts and rotating respectively on said axes, and connecting elements between said disks, said connecting elements comprising pins having at either end laterally offset bearing portions engaging respectively in said disks.

- 10 6. In a continuous rod cigarette machine, the combination with a cutoff blade, of mechanism for moving said blade in an orbital path oblique to the cigarette rod to cause the edge of the blade to traverse the rod and follow its movement, including a shaft for said blade, oppositely disposed mounts for said shaft revolving respectively on axes laterally offset from each other, said shaft having spherical journals and said mounts having 20 cooperating spherical bearings.
- 15 7. In a continuous rod cigarette machine, the combination with a cutoff blade, of a blade holding element therefor, and mechanism for carrying said blade in an orbital path to cause the edge of the blade to traverse the rod and follow its movement, said mechanism including oppositely disposed mounts fixed to said element revolving on 25 separate parallel axes.
- 20 8. In a continuous rod cigarette machine, the combination with a cutoff blade, of a blade holding element therefor, mechanism for carrying said blade in an orbital path to cause the edge of the blade to traverse the 30 rod and follow its movement, said mechanism including oppositely disposed mounts in which said element is journaled revolving on separate parallel axes, and spaced parallel disks respectively carrying said mounts and 35 rotating on said axes.

- 40 9. In a continuous rod cigarette machine, the combination with a cutoff blade, of a blade holding element therefor, mechanism for carrying said blade in an orbital path to cause the edge of the blade to traverse the rod and follow its movement, said mechanism including oppositely disposed mounts for 45 said element revolving on separate parallel axes, said mounts cooperating with said element and said mechanism to provide a universal connection with said mechanism at each of said mounts.

In testimony whereof, we have signed our names to this specification.

50 WILHELM BERTIL BRONANDER.
